[57] ABSTRACT

An electron beam amplifier tube has a traveling wave output circuit electrically isolated from the signal input circuit so that the output circuit is excited only by beam electron current. The upstream end of the output circuit is terminated with an impedance which reflects a substantial part of the backward wave energy flowing toward the upstream end. The phase and amplitude of the reflection may be chosen to reinforce the beam-circuit interaction, thereby improving tube efficiency.

ELECTRON BEAM AMPLIFIER TUBE WITH MISMATCHED CIRCUIT SEVER

The invention herein described was made in the course of or under a contract or subcontract thereunder, (or grant) with the Department of the Air Force.

FIELD OF THE INVENTION

The invention relates to microwave amplifier tubes wherein a beam of electrons interacts with an electromagnetic wave on a slow-wave circuit which wave travels with velocity approximately equal to that of the electron beam. Such tubes include crossed field amplifiers, linear beam traveling wave tubes and hybrid traveling wave tubes with klystron-like driver sections known by the registered trademark "Twystron". These types of tubes provide amplification over a wide frequency range and can be designed for high power output and high efficiency.

In a traveling wave tube, the gain increases with the length of the slow-wave interaction circuit. When the gain becomes too high, e.g., 20 db or more, instabilities arise due to reflection of wave energy from the inevitable small transmission line impedance mismatches at the ends of the circuit. The reflected energy is re-amplified, producing instability.

PRIOR ART

In prior art tubes, the instability difficulty has been reduced by severing the circuit at one or more points to form isolated sections with reduced individual gain. Each upstream and downstream severed end is customarily terminated in a dummy load matched to its characteristic transmission line impedance. At the sever, the wave energy on the circuit is dissipated in the load. The following downstream section of circuit is excited only by the alternating current component of the electron beam which carries signals only in the forward direction with no feedback.

The matched termination customarily provided at the upstream end of a downstream severed section was intended to prevent reflection of any wave traveling backward upstream in that section, because amplification of the wave reflected downstream creates regeneration.

In the final output section of the circuit whose downstream end is connected via a transmission line to a useful, external load, particularly large waves may be reflected backward by unavoidable mismatch of the useful load. It has therefore been common practice to try to obtain the best possible match to the dummy load at the upstream end of the output circuit section, and it has been generally assumed that a perfect match will give optimum performance.

It has been widely believed in the traveling wave tube art that the gain in the output section must be relatively high to provide efficient generation of output power. For example, "Why a Circuit Sever Affects Traveling Wave Tube Efficiency" by A. W. Scott, IRE Transactions on Electron Devices, ED9, No. 1, page 35, teaches that in a typical high power tube at least 26 db of growing-wave gain is needed. With this regime of gain, a well matched sever termination is of course necessary.

As disclosed in U.S. Pat. No. 3,825,794 issued July 23, 1974 to Robert J. Butwell and assigned to the present assignee, it has recently been discovered that by providing a tightly bunched electron beam entering the

output circuit, one can obtain good efficiency with less than 13 db gain in the output section.

Some of the prior art circuit terminations have been used in severed circuit traveling wave tubes and others in Twystron hybrid amplifiers as described in U.S. Pat. No. 3,289,032 issued Nov. 29, 1966 to R. R. Rubert and R. L. Perry and assigned to the present assignee. In a hybrid tube the signal is carried from the klystron cavities to the traveling wave output circuit only by the bunched beam, exactly as in a severed TWT, so the requirements of the output circuit are the same for both types of tubes.

SUMMARY OF THE INVENTION

The principal object of the present invention is to provide a wide-band, electron beam, microwave amplifier tube with improved efficiency.

Another object is to provide a tube whose performance is insensitive to wave reflections from its load.

Another object is to provide a tube of simplified construction.

These objects have been achieved in a beam tube with a short, traveling wave output circuit by providing at the upstream end of the circuit a terminating impedance which reflects a substantial portion of any wave energy flowing backward toward the upstream end. With proper values of the phase and amplitude of the reflection the forward wave reflected by the termination adds to the wave excited by the beam to enhance the interaction efficiency.

In direct opposition to previously held belief that the output circuit must have high gain and that it must have a matched termination, the present invention has produced increased efficiency with a short, low gain circuit. Since the gain of the output circuit is low, changes in output load match produce smaller perturbations of the tube performance. Also, the short traveling wave circuit is simpler to fabricate and cheaper than previous long, high gain circuits.

BRIEF DESCRIPTION OF THE DRAWINGS

FIG. 1 is a schematic elevation view, partly in section, of a hybrid linear beam amplifier embodiment of the invention.

FIG. 2 is an enlarged section of the output circuit of the amplifier of FIG. 1.

FIG. 3A is an enlarged plan view section of the circuit of FIG. 2 along the line 3A-3A.

FIG. 3B is an isometric view of a cavity of an alternative slow-wave circuit.

FIG. 4 is an elevation section of a portion of another embodiment of the invention corresponding to section 4 of FIG. 3A.

FIG. 5 is a view similar to FIG. 4 of still another embodiment.

FIG. 6 is a view similar to FIG. 4 of still another embodiment.

FIG. 7 is a schematic section of a crossed-field amplifier embodying the invention.

DESCRIPTION OF THE PREFERRED EMBODIMENTS

The present invention is applicable to any electron beam amplifier tube wherein radio frequency power is extracted from the beam by interaction with an electromagnetic wave traveling at approximately the beam velocity on a severed circuit. Such tubes include linear

beam traveling wave tubes and hybrid Twystron amplifiers as well as crossed-field amplifiers with injected beam. For clarity of illustration the Twystron hybrid embodiment will be described in detail.

FIG. 1 illustrates a hybrid Twystron amplifier. A cylindrical electron beam is formed by an axially symmetric gun 10 comprising a concave thermionic cathode 11, as of porous tungsten impregnated with barium aluminate, and surrounded by a beam-focusing electrode 12 as of austenitic stainless steel operated at the same potential as cathode 11. Gun 10 is mounted on a metallic base (not shown) sealed to a ceramic insulating cylinder 21, as by brazing. The other end of cylinder 21 is brazed to a steel cup 22 surrounding gun 10. A central aperture in cup 22 is brazed to a copper anode electrode 23 containing a central axial aperture 24.

In operation, a negative voltage applied to gun 10 with respect to anode 23 draws a converging electron beam through aperture 24. Surrounding anode 24 is an iron polepiece 25 for directing the field of a surrounding solenoid magnet (not shown) axially of the beam to focus it in an extended cylindrical outline.

The beam passes through a series of klystron-type cavities 30, 31, as of copper, provided with reentrant annular drift tube sections 32 defining beam interaction gaps 33. The first, upstream cavity 30 is coupled via a conductive loop 34 to a coaxial transmission line 35 carrying the input drive signal for the amplifier. The signal is amplified by the well-known klystron velocity modulation process. The resonant frequencies and Q's of cavities 30, 31 are staggered as taught by the aforesaid U.S. Pat. No. 3,289,032 to provide a tightly bunched beam over a wide frequency range such as 10% of the center frequency.

The bunched beam enters a traveling wave output circuit 40 comprising a series of cavities 41 (FIG. 2) as of the cloverleaf type described in U.S. Pat. No. 3,233,139 issued Feb. 1, 1966 to Marvin Chodorow and assigned to the present assignee. The cavities are mutually coupled by radial slots 42 (FIG. 3A) to form a bandpass circuit propagating a forward-fundamental slow wave for interaction with the electron beam in the well-known traveling wave tube fashion. Toward the output end of the circuit the axial heights of the cavities are tapered to smaller values to reduce the circuit wave velocity to match the reducing velocity of the electrons as kinetic energy is extracted from them. The tapering principle is described in U.S. Pat. No. 3,374,390 issued Mar. 19, 1968 to J. A. Ruetz, W. H. Yocom and Rene M. Rogers and assigned to the present assignee.

The final cavity 43 is coupled through an iris aperture 44 to a reduced height rectangular output waveguide 45 which is matched by a tapering height section 46 to a standard height output waveguide 47. Interposed between two sections of guide 47 is a short section of cylindrical guide 48 sealed by a ceramic vacuum window 49 as described in U.S. Pat. No. 2,958,834, issued Nov. 1, 1960 to R. S. Symons and A. E. Schoennauer and assigned to the present assignee.

After passing through traveling wave output circuit 40 the beam goes through a second magnetic polepiece 50 which terminates the axial focusing field. The beam then expands and is collected on the inner surface 51 of a collector 52, as of copper, mounted on polepiece 50 via a cylindrical ceramic insulator 53. Collector 52 is cooled by water circulating through inlet and outlet

pipes 54 and small enclosed channels (not shown) in the copper collector walls.

When the tube is operated, the electron beam enters output traveling wave circuit 40 with the electrons gathered into periodic bunches by the velocity modulation in the klystron section. The alternating space current component represented by the bunches induces rf circulating current in the circuit cavities. This in turn produces an rf voltage wave traveling with the beam which increases the bunching, so the signal is amplified. At the same time energy is transferred from the beam's kinetic energy to the circuit wave which is carried to the useful output.

The electromagnetic fields in any given cavity couple energy through the coupling slots to its two adjacent cavities, upstream and downstream, in approximately equal amounts. The downstream fields add in proper phase to those generated in succeeding downstream cavities to produce the growing forward traveling wave. In traveling wave tubes where the circuit is many wavelengths long and the gain per circuit period is small, the upstream fields of the successive circuit periods add up in a cancelling phase, so there is very little backward flow of power. However, in very high power tubes the gain per cavity may be as much as 3 db. In this case the cancellation of backward waves is very imperfect. In the upstream cavities the backward wave power may sometimes even exceed the forward wave and may be a sizeable fraction of the tube's output power.

Previous TWT practice and theory has been based on the belief that the upstream end of the circuit should be terminated in a matched impedance so that any backward wave is absorbed at the circuit input. According to the present invention, it is found that improved efficiency can be obtained when all or a substantial portion of the backward wave incident on the upstream end of the output circuit is reflected downstream. The reflection must be of a carefully selected phase and amplitude such that the reflected wave adds to the forward waves generated in the first few cavities to produce the proper phase and amplitude of rf voltage to enhance the bunching process. The interaction is complex and not definable in terms of a simple analogy. Results can be predicted by digital computer calculations leading to specific designs suitable for a particular tube. According to these calculations the generalized concept of a mismatched sever termination should provide improved efficiency in a wide variety of tubes. Experimental tests on one tube indicate improved efficiency from 44% with a matched termination to 51% with a beneficial mismatch.

Returning now to FIG. 2, the upstream cavity 60 of traveling wave circuit 40 is coupled via an iris aperture 61 to a waveguide 62 which tapers from the height of cavity 60 to a standard height. In this embodiment circuit 40 is matched for backward traveling waves into guide 62. The desired wave reflection is caused by an impedance transformer 63 in guide 62. Any standard impedance transformer may be used. Transformer 63 is a capacitive iris for example. The amplitude of the reflection is controlled by the height of the iris and the phase by its distance from cavity 60. More complex microwave transformers may be used to adjust the phase and amplitude of the reflection to be a desired function of frequency as is well-known in the art of microwave impedance matching.

Wave power not reflected by transformer 63 proceeds down guide 62 and is absorbed by a matched load termination 64, for example, a block of ceramic loaded with carbon particles and tapered in height to provide a broadband match.

FIG. 3A illustrates a cloverleaf cavity, as indicated in FIG. 2, with the upper lid removed to show coupling slots 42. FIG. 3A also shows the coupling of upstream cavity 41 to sever load waveguide 62 through iris aperture 61. The width of iris 61 is adjusted to provide the correct coupling to match the impedance of slow-wave circuit 40 to waveguide 62.

FIG. 3B shows an alternate cavity useful as an element of a traveling wave circuit according to the present invention. Here the cavity 41' is a simple cylinder with short drift tubes 70 projecting from each end wall 71. Coupling to adjacent cavities is through iris slots 72. In this cavity circuit the fundamental traveling wave is a backward wave, but drift tubes 70 introduce space harmonic fields with a forward component which can interact with the beam.

FIG. 4 shows a different embodiment of the invention as applied to the same type of slow-wave circuit 40 as shown in FIGS. 1 and 2. In FIG. 4, waveguide 62 is terminated in a short circuit 65 at a distance from cavity coupling iris 61 selected to reflect backward wave energy into cavity 60 in the proper phase. The amplitude of the reflected wave is controlled by a button of lossy dielectric material 66, as of carbon grains dispersed in beryllium oxide ceramic, disposed within cavity 60 to absorb some of the energy therein. In some embodiments a complete reflection may be desired and lossy button 66 would then be omitted.

FIG. 5 illustrates another embodiment using a slow-wave circuit 40 similar to the circuit of FIGS. 1 and 2. In FIG. 5 the phase of the reflected wave is controlled by the resonant frequency of the first cavity 60'. By making the distance d' between noses 72' different from the corresponding distance d between noses 72 of the other resonators 41 of circuit 40, the resonant frequency of cavity 60' is set so that energy is reflected in the desired phase. The amplitude of the reflection is determined by the size of iris 61' which determines the amount of backward wave energy coupled into waveguide 62 and absorbed in load 64. In this embodiment the backward wave is not matched to the load waveguide but partially reflected at iris 61'.

FIG. 6 shows still another embodiment wherein both phase and amplitude of the backward wave are controlled internally of first cavity 60'. The resonant frequency, determined by nose spacing d' , determines the phase, and the cavity Q, determined by lossy button 66, determines the amplitude. In some embodiments button 66 may be omitted to produce complete reflection.

FIG. 7 shows a highly schematic embodiment of the invention in an injected-beam crossed field amplifier. Inside a vacuum envelope 70 is a thermionic cathode 72 heated by a radiant heater 73. A beam of electrons 71 is drawn from cathode 72 by an accelerating anode 74 at a positive potential 86 with respect to cathode 72. A uniform magnetic field B perpendicular to the cathode and anode surfaces directs the beam perpendicularly to its initial direction and away from the cathode. The beam enters an interaction region between a flat, extended sole electrode 75 operated at a potential 85 negative to cathode 72 and an extended slow wave circuit 76, 77 operated at a potential 87 positive to accel-

erating anode 74. In the illustrated embodiment circuit 76, 77 is structurally integral with vacuum envelope 70, the metallic parts of which are operated at the dc potential of circuit 76, 77.

Electron beam 71 drifts lengthwise of sole electrode 75 and circuit 76, 77 under the influence of the crossed electric and magnetic fields. The field amplitudes are selected so that the average drift velocity approximates the wave velocity on circuit 76, 77.

Circuit 76, 77 is severed into two parts 76 and 77 which are isolated against wave energy transmission therebetween by a non-propagating sever section 78. The input circuit section 76 is matched at its upstream end to a waveguide 79 for introducing the input microwave signal. The signal is amplified by synchronous interaction with beam 71.

At sever 78 circuit 76 is matched to a load waveguide 80 terminated in a non-reflective load 81. The rf signal is carried over to output circuit 77 by the ac component of current on beam 71. The upstream end of circuit 77 is coupled to a waveguide 82 provided with a wave-reflecting transformer 83 and a matched load 84 to absorb non-reflected energy. Backward wave energy on circuit 77 is reflected in guide 82 with a phase and amplitude selected to enhance the interaction of the combined forward wave and the electron beam. The forward wave is amplified in output circuit section 77 and matched at the downstream end thereof into output waveguide 85 for conduction to a useful load.

The several embodiments described to clarify the invention are illustrative only. Many other embodiments will be apparent to those skilled in the art. The invention is therefore intended to be limited only as described in the following claims and their legal equivalents.

What is claimed is:

1. An electron beam amplifier tube comprising; a vacuum envelope, means for forming and directing a beam of electrons, means for collecting said electrons, first circuit means for modulating said beam at a high frequency, second circuit means downstream of said first circuit means and isolated therefrom to prevent propagation of electromagnetic energy therebetween, said second circuit means comprising, a slow-wave circuit capable of propagating a traveling wave in energy-exchanging relationship with said beam and having an upstream end adjacent said first circuit means and a downstream end removed from said upstream end in the direction of flow of said electrons,

an output transmission line matched to said downstream end of said slow-wave circuit to couple into said transmission line a greater part of the wave energy flowing in said slow-wave circuit toward said downstream end, and terminating means at said upstream end of said slow-wave circuit, the improvement wherein,

said terminating means comprises means for reflecting into a downstream flowing wave a selected substantial portion of wave energy flowing upstream in said slow wave circuit toward said upstream end, the reflected wave having a phase with respect to said upstream wave selected to increase the efficiency of said tube over a wide operational frequency range.

2. The apparatus of claim 1 wherein said reflecting means comprises means for reflecting substantially all of said wave energy flowing in said slow-wave circuit.

3. The apparatus of claim 1 wherein said reflecting means comprises a transmission line coupled to said upstream end of said slow-wave circuit and containing a wave-reflective impedance discontinuity.

4. The apparatus of claim 3 wherein said transmission line further contains an attenuator.

5. The apparatus of claim 3 wherein said wave-reflective discontinuity is a short circuit.

6. The apparatus of claim 1 wherein said slow-wave circuit is a series of mutually-coupled periodic elements.

7. The apparatus of claim 6 wherein said periodic elements are cavities with conductive walls.

8. The apparatus of claim 6 wherein said reflecting means comprises one of said periodic elements with electrical characteristics different from succeeding

downstream elements.

9. The apparatus of claim 8 wherein said one of said elements has a self-resonant frequency different from said succeeding elements.

10. The apparatus of claim 8 wherein said one of said elements comprises energy-attenuating means.

11. The apparatus of claim 9 wherein said portion of said wave energy is at least one fourth.

12. The apparatus of claim 6 wherein said reflective means comprises one of said periodic elements which is electromagnetically coupled only to succeeding downstream elements.

13. The apparatus of claim 12 wherein said one of said elements comprises energy-attenuating means.
